TOBACCO BOX

Charles Snyder, Newark, N. J.

Application July 3, 1936, Serial No. 88,874

2 Claims. (Cl. 206—38)

This invention relates to tobacco boxes, one of the objects being to provide a simple and inexpensive device of this character which can be used as a smoker's kit for holding a pipe, pipe cleaners, matches, etc. as well as a supply of tobacco.

Another object is to provide a novel form of closure for the box which can be shifted to permit convenient removal of any of the contents but which normally is positioned to conceal and protect the contents.

A still further object is to provide a device of this character having the appearance of an ordinary tobacco box and adapted to be conveniently carried in a pocket.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a front elevation of the box, the cover being moved into position to permit removal of the pipe, matches and/or pipe cleaners.

Figure 2 is a similar view showing the cover shifted to release the tobacco.

Figure 3 is a vertical transverse section through the cover while in normal position on the container.

Figure 4 is a section on line 4—4, Figure 3.

Figure 5 is a section on line 5—5, Figure 3, the pipe being shown in plan.

Figure 6 is a section on line 6—6, Figure 3.

Referring to the figures by characters of reference 1 designates the box or container portion of the device which can be made of any size and proportions but is preferably shaped substantially like the ordinary tobacco box. It is closed at the bottom as shown at 2 and is also closed at the top as indicated at 3. Vertical and horizontal partitions 4 and 5 respectively cooperate with the bottom and walls of the box to form a tobacco compartment 6 and a portion of one wall 50 of this compartment is cut away to provide an opening 7 whereby tobacco can be placed in and removed from the compartment.

Another partition 8 is interposed between and parallel with partition 4 and the adjacent side 55 wall of the box, thereby to form separate com-

partments 9 and 10. These compartments, which extend to the bottom of the box, open at their upper ends into the space 11 provided between the top 3 and the partition 5. This space is so proportioned as to hold the bowl B of a pipe P, 5 the stem portion of the pipe being removably seated in the compartment 10.

The other compartment 9 is adapted to hold pipe cleaners C and in order that both the cleaners and the pipe may easily be removed from or 10 placed in the box, the upper portion of one wall of each compartment 9 and 10 is removed to form a side opening 12 and the same side of the bowl-receiving space is also left open as shown.

A transverse partition 13 is interposed between 15 partition 5 and the top 3 and is joined by partition 14 to another transverse partition 15. The partition 14 does not extend to the top 3 but is spaced therefrom to leave an outlet slot 16 from which matches can be removed from the receptacle defined by partitions 13, 14 and 15 and one 20 wall of the box, as shown particularly in Figures 4 and 5. This container, indicated at 17, does not extend the entire thickness of the box 1 because partition 14 is set back from the adjacent box wall so as to carry a striker plate 25 or sheet 18 formed of metal, sand paper or other material held to the partition by ears 19 which lap the ends of the striker or abrasive member.

The cover of the box is in the form of a sleeve 20 which is fitted snugly to the outer surface of the box and is slidable therealong in either direction, this sleeve being of the same length as the box and being open at its ends.

Obviously when the cover is in its normal position, as shown in section in Figure 3, it will close the opening 7 and also the open front portions of the compartments 9 and 10, space 11 and slot 16. It will also conceal the abrasive member 18.

When it is desired to fill the box with tobacco, the cover 20 is slid upwardly to expose opening 7 and the tobacco can then be inserted through this opening. Thereafter the cover is slid back 45 to conceal the opening.

To remove the pipe, the cover is slid downwardly to expose the bowl and the upper portion of the pipe stem as shown, for example, in Figure 1. Sufficient movement of the pipe is permitted to allow its convenient withdrawal when the cover is thus shifted, and by inverting the box one or more matches can be delivered through slot 16. When the cover is in this position the pipe cleaners also can be removed.

After withdrawal of the pipe, cover 20 can again be slid upwardly to expose opening 7 and permit removal of tobacco to be used in filling the bowl.

5 What is claimed is:

1. A tobacco box including a container, a tobacco compartment therein having an opening in its front wall and spaced from one side and end of the box to provide a compartment for holding a pipe stem and bowl, one end of the tobacco compartment providing a support for the bowl and one end portion of the pipe compartment being open at one side, and a sleeve-like closure surrounding and slidable on the box in one direction to expose the opening of the tobacco compartment, and in the opposite direction to expose the opening in the pipe compartment, said openings being normally closed by the closure.
- 10 15 20 2. A tobacco box including a container having

partitions therein dividing the interior of the container into a tobacco compartment, a pipe compartment, a compartment for pipe cleaners, and a match compartment, one of the partitions forming the tobacco compartment constituting 5 means for supporting the pipe bowl in position to substantially close one end of the pipe cleaner compartment, said pipe and cleaner compartment having one wall cut away at one end to facilitate removal of the pipe and cleaners, and there being an opening in one wall of the tobacco compartment, and a sleeve-like closure slidable on the box in one direction to expose the opening of the tobacco compartment, and in the opposite direction to expose the openings in 10 the other compartments, there being a slot in one wall of the match compartment, said closure being normally positioned to close all of the 15 openings.
